UNITED STATES PATENT OFFICE.

WILLIAM J. TYSON, OF NEW YORK, N. Y.

BURGLAR-ALARM LOCK.

Application filed December 4, 1925. Serial No. 73,217.

This invention relates to a burglar-alarm-lock, and has as its principal object the provision of means whereby an audible alarm is sounded the moment anyone attempts to operate the lock. This alarm is produced by the single motion of the key entering the lock.

An object of this invention is to provide means in combination with the lock whereby the mere insertion of any key, blank, or other instrument, whether its fits the tumblers or not, will complete an electric circuit and cause a signal to be given. This signal or alarm continues so long as the key, blank, or other instrument remains in the lock.

A further object of this invention is to provide a device of the character described which will be readily adaptable to various kinds of cylinder locks for rendering the same burglar-proof, by means of the sounding of an audible alarm.

A further object of this invention is to provide a very simple construction, which will not affect the strength of the lock proper, and still perform its intended functions efficiently.

I am aware of attempts that have been made heretofore to solve the problem of burglar-proof locks, by arranging the signal to be given when the bolt is operated, and the door opened. It stands to reason that a burglar, having succeeded in forcing an entrance, and seeing an open door before him, is not going to retire when he is already in the house. In my invention, the alarm is given the moment the key or any other instrument is inserted, and before the bolt is moved. This has the effect of scaring the burglar away before any damage is done. Such an alarm acts as the reminder to the rightful occupants who are prone to forget their keys in the doors of their apartments.

With these, and other objects in view, the invention will be hereinafter more particularly described, and the combination and arrangement of parts will be shown in the accompanying drawings and pointed out in the claims which form part of this specification; it being understood that various changes in the size, form, proportion, and minor details of construction, within the scope of the appended claims, may be resorted to without departing from the spirit, or sacrificing any of the advantages of, the

invention. Reference will now be had to the drawings, wherein like numerals of reference designate corresponding parts throughout the several views, in which:

Fig. 1 is a view, partly in section, showing a standard make Yale or tumbler lock, which has been made burglar-proof by means of my invention.

Fig. 2 is a cross sectional view of the lock; the section being taken as on the line "x—x" in Fig. 1.

Fig. 3 is a view of the cylinder barrel 1, showing a channel 9 in the cylindrical wall.

Fig. 4 is a view of the tumbler cylinder or key drum 10 showing a recess 11 lengthwise on the keyway side.

Fig. 5 is an elevation of a terminal carrier 3, having two contact terminals 4 and 5 which are connected with electric bell 75 wires 12 and 13.

Fig. 6 is a view showing an insulation member 6.

Fig. 7 is a view of a box structure 8 for housing the terminal carrier 3, showing a semi-circular aperture 14 for the entrance of two wires forming an electric circuit.

Fig. 8 is a top view of the box shown in Fig. 7.

Fig. 9 is a view, partly in section, showing another make of cylinder which is designed to fit in a mortise lock. The cylinder of this form of lock is provided with a thread 21, forming a ready means of fastening the cylinder to the body of the lock.

Fig. 10 is a cross sectional view of the lock, the section being taken as on the line "y—y" in Fig. 9.

Fig. 11 is a view showing a circular plate 95 15, used as a housing for a rectangular shaped contact member 16, as is shown in Fig. 12.

Fig. 12 is a perspective view of the contact member 16.

Fig. 13 is a perspective view of the terminal carrier 17 having two contact terminals 18 and 19.

Fig. 14 is a perspective view showing an insulation member 20.

Part No. 1, shown in Fig. 1 is a section of the cylinder barrel, showing the key 2 inserted. Part 3 is a nonconducting terminal carrier in which has been incorporated two terminals 4 and 5 of an electric circuit; placed beneath the terminal carrier is an insulation member 6 which is used to insu-

late a spring 7. The terminal carrier 3 and the spring 7 are housed in a box structure 8 which is permanently attached to the lock barrel. Thus, the coil spring presses the terminals upwards against the barrel, and in line with the key slot. This upward motion is arrested and limited by the lower end of the barrel which has been hollowed out, forming a channel 9, as is best shown in Fig. 10, so as to allow the terminal holder 3 to enter and move up a pre-determined distance. Thus the terminal carrier can raise the terminals to within, approximately, one thirty-second of an inch of the lower end of the key slot, at the recess 11. When the key 2 is inserted in the key slot, it extends approximately, one thirty-second of an inch below the slot, at the recess 11, and thus comes in contact with the terminals 4 and 5 and completes the electric circuit, and causes an alarm to be sounded.

To prevent the terminals from coming in contact with the key drum, or tumbler cylinder 10, as best shown in Fig. 2, its lower or slotted end has been partly cut away to form a recess or hollow space 11 into which the terminals enter.

Referring to Fig. 9, it will be noted that the cylinder has a thread 21 which is used to screw the cylinder into the body of the lock, and fasten it thereto.

Part No. 16 as best shown in Fig. 10, acts as an intermediary between the key and the terminals. Part No. 17 represents the non-conducting terminal carrier. Part No. 22 represents a spring used for separating the contact member 16 from the terminal carrier 17, as best shown in Fig. 10.

The electric bell 25, which may be mounted at any convenient point, may be arranged in circuit with any supply of electric current, such as batteries 26. It will readily be noted that in this construction the coil spring 22 pulls the contact member up and away from the terminals.

Referring to Fig. 10, it will be noted that when the key is inserted in the slot, it will

displace the contact member 16, and force it down until it touches the two terminals 18 and 19, as best shown in Fig. 9, thus completing the electric circuit, and causing an alarm to be sounded.

The difference between Fig. 1 and Fig. 9 is, the construction shown in Fig. 1 applies to any Yale lock without any thread on the cylinder barrel, while the construction shown in Fig. 9 is used only in a mortise type cylinder lock, in which there is a thread on the cylinder barrel.

I have thus described two embodiments of my invention. I claim as new, and desire to secure by Letters Patent,

1. A key actuated switch lock, comprising a cylinder barrel, having a channel in the cylindrical wall opposite the tumbler holes; a tumbler cylinder, having a recess lengthwise on the keyway side; a box structure below the recess; an insulating terminal carrier, having two electric terminal contacts, housed within the box, and facing the keyway; an insulation member, below the terminal carrier; a spring, exerting a pressure against the key-shank, and insulation member, when the key is inserted in the lock.

2. A key actuated switch lock, of the tumbler type, known as Yale locks; comprising a cylinder barrel, having a channel in the cylindrical wall, opposite the tumbler holes; a tumbler cylinder, having a recess lengthwise on the keyway side; a box structure, below the recess, and permanently fastened to the lock; an insulated terminal carrier, having two electric terminal contacts, housed within the box, and facing the keyway (said terminals being on the same level plane, and in line with the keyway); an insulation member below the terminal carrier; a spring, exerting a pressure against the key-shank, when the key is inserted in the lock.

Signed at the city of New York, in the county of New York and State of New York, this 23rd day of November, A. D., 1925.

WILLIAM J. TYSON.
